[57] CLAIM

The ornamental design for a toy racing car, substantially as shown and described.

DESCRIPTION

FIG. 1 is a front perspective view of a toy racing car, showing my new design;

FIG. 2 is a top plan view thereof, shown on a slightly enlarged scale;

FIG. 3 is a right side elevational view thereof;

FIG. 4 is a front elevational view thereof, and

FIG. 5 is a rear elevational view thereof.

The side of the toy racing car opposite the view of FIG. 3 is substantially a mirror image thereof.

FIG. 1

FIG. 2

FIG. 3

FIG. 4

FIG. 5
